CLAIM

The ornamental design for a water cooler, as shown and described.

DESCRIPTION

FIG. 1 is a perspective view of a water cooler showing our new design;

FIG. 2 is a front view thereof;

FIG. 3 is a right side view thereof;

FIG. 4 is a left side view thereof;

FIG. 5 is a rear view thereof;

FIG. 6 is a top plan view thereof;

FIG. 7 is a bottom plan view thereof;

FIG. 8 is an in-use perspective view thereof showing a fold out support tray; and,

FIG. 9 is a perspective view of a water cooler showing a second embodiment of my new design with stippling indicating contrasting color and texture.

The broken lines in the drawings are included for the purpose of illustration and form no part of the claimed design.
